UNITED STATES PATENT OFFICE.

ARMITAGE S. C. FORBES AND HARRY R. P. FORBES, OF LOS ANGELES, CALIFORNIA.

DESIGN FOR A BOOKHOLDER.

61,292.

Specification for Design.

Patented Aug. 1, 1922.

Application filed November 15, 1920. Serial No. 424,308. Term of patent 3½ years.

To all whom it may concern:

Be it known that we, ARMITAGE S. C. FORBES and HARRY R. P. FORBES, both citizens of the United States, residing in the city of Los Angeles, county of Los Angeles, State of California, have invented a new and original and ornamental Design for Bookholders, of which the following is a specification, reference being had to the accompanying drawing, forming a part thereof.

The figure is an isometric view showing the outer surface of one of the ends of our book holder.

Our invention relates to a pair of members each of which is composed of a body piece and a base piece at one end of and attached to the body piece, preferably by a hinge, which is at right angles to the body piece when positioned for use and projects beneath the books at the end of the row.

We claim:

The ornamental design for a book holder as shown.
